UNITED STATES PATENT OFFICE.

JAMES TOTHAM, OF NEW HAVEN, CONNECTICUT, ASSIGNOR TO THE PECK BROS. & COMPANY, OF SAME PLACE.

DESIGN FOR A BASIN-COCK.

SPECIFICATION forming part of Design No. 25,950, dated August 18, 1896.

Application filed December 23, 1895. Serial No. 573,142. Term of patent 14 years.

To all whom it may concern:

Be it known that I, JAMES TOTHAM, of New Haven, in the county of New Haven and State of Connecticut, have invented a new Design 5 for Basin-Cocks; and I do hereby declare the following, when taken in connection with the accompanying drawing and the letters of reference marked thereon, to be a full, clear, and exact description of the same, and which 10 said drawing constitutes part of this specification and represents a view in side elevation of a basin-cock embodying my design.

This invention relates to a design for basin-cocks, and the design consists in the configuration as herein described and shown in the 15 accompanying illustration.

My newly-designed basin-cock has a horizontally-arranged spout A, turned downward at its outer end and connected at its inner

end with the central portion B of the body, 20 which is surmounted at its upper end with a cap C and supported at its lower end upon a base D. The central portion of the body is convexed and separated by small fillets b b from convex bands B' B'. The base D is cone-shaped in general form and grooved to present a stepped appearance. The cap C has a 25 faceted flange C' at its lower end.

I claim—

The design for a basin-cock as herein 30 shown and described.

In testimony whereof I have signed this specification in the presence of two subscribing witnesses.

JAMES TOTHAM.
